CLAIM

The ornamental design for a helmet, as shown and described.

DESCRIPTION

FIG. 1 is a front perspective view of a helmet;
FIG. 2 is a rear perspective view thereof;
FIG. 3 is a bottom perspective view thereof;
FIG. 4 is a front elevation view thereof;
FIG. 5 is a rear elevation view thereof;
FIG. 6 is a right side elevation view thereof;
FIG. 7 is a left side elevation view thereof;
FIG. 8 is a top plan view thereof; and,
FIG. 9 is a bottom plan view thereof.

The dashed lines represent unclaimed features of the helmet that form no part of the claimed design.
